Mueller Brothers
ATTORNEY

UNITED STATES PATENT OFFICE.

WILLIAM S. HUNKINS, OF HOLLYWOOD, CALIFORNIA.

PIN TUBE.

Application filed October 7, 1924. Serial No. 742,269.

To all whom it may concern:

Be it known that I, WILLIAM S. HUNKINS, a citizen of the United States of America, residing at Hollywood, California, have invented a new and useful Pin Tube, of which the following is a specification.

My invention relates to certain new and useful improvements in so-called pin tubes, which function to support the pin portion of

10 a safety pin throughout a substantial portion of its length, so that, when under strain, it will not bend and thereby dislodge the point from the shield.

The main object of the present invention 15 is to provide a tube which may be easily secured in place on a fabric support, and which, when secured in place, will not move out of position endwise or otherwise.

In the drawings—

20 Fig. 1 is a side elevation, partly in section, of a preferred form of tube, the same being on a very much enlarged scale;

Fig. 2 is a similar view, showing the tube held in place on a piece of webbing;

25 Fig. 3 is a view similar to Fig. 2, illustrating a modification;

Fig. 4 is a similar view, illustrating another modification.

In the form shown in Figs. 1 and 2, 1 represents the main body of the tube, having

30 two expanded or bulged out annular enlargements 2—2 adjacent to the ends thereof and forming abutment shoulders for holding loops, 3 represents a short strip of

35 webbing, of a width approximately the length of the tube. 4—4 represent loops or thread or the like by which the tube is secured to said webbing. It will be observed that these loops terminate adjacent

40 to the abutment shoulders 2—2, and thus endwise displacement of the tube within the webbing is prevented. Ordinarily, if the tube is attached to a piece of webbing, such

45 as indicated in Fig. 2, the webbing would be folded on itself to form a short tab, the tube being located within the fold or bight thereof. These articles, including the web

50 tab, may be vended as complete articles of manufacture, ready to be stitched onto a garment at any desired place; or, in some instances, the bare tubes may be vended so

55 that they may be sewed directly onto the webbing or onto a garment by the purchaser.

In Fig. 3 I have shown a modification, in

which a single abutment bulge occurs at about the middle of the tube, as indicated at 5. The presence of this abutment between the stitches or loops 6—6, which in this instance are located on opposite sides of the 60 enlargement, serves to prevent the endwise displacement of the tube after it is secured in place. In this case the opposite sides of the bulge form, in effect, two shoulders.

In Fig. 4 I have shown another modification, in which the abutment shoulders appear directly at the ends of the tube, as indicated at 7—7. These abutments are formed by flaring outwardly the ends of the tube. Here again the tube may be stitched 70 to the webbing 3 by thread loops 8 in the same manner as in Fig. 2, and the shoulders 7—7 will prevent the endwise displacement of the tube relatively to the webbing 3. In this construction the shoulders 7—7, being 75 bell shaped, facilitate the easy entrance of the pin point into the tube and thereby perform a double function.

What I claim is:

1. As an article of manufacture, a pin 80 tube of the character described, comprising a tubular body having an integral expanded portion constituting an abutment for engaging the sides of connector loops extended around said body.

2. As an article of manufacture, a pin tube of the character described, comprising a tubular body having an integral expanded portion constituting an abutment for engaging the sides of connector loops extended 90 around said body, one of said abutments being provided adjacent each of said tube.

3. In a pin tube of the character described, a tubular body having an integral expanded portion directly at each end thereof formed 95 by flaring outwardly the ends of said tube to provide two loop-engaging abutments and two enlarged pin entrances.

4. As an article of manufacture, a tab comprising a piece of webbing, a tube arranged transversely thereof, connector loops for holding said tube to said webbing, a portion of the tube being expanded outwardly to form an abutment for said connector loops, said connector loops being located 100 closely adjacent to said abutment to check endwise movement of said tube relatively to said webbing.

WILLIAM S. HUNKINS.
